Primary Examiner — T. Chase Nelson*Assistant Examiner* — Mark Cavanna(74) *Attorney, Agent, or Firm* — Mintz Levin Cohn Ferris Glovsky and Popeo, P.C.(57) **CLAIM**

The ornamental design for an enclosure for a patient monitor, as shown and described.

DESCRIPTION

FIG. 1 is a front view of an enclosure for a patient monitor showing our new design;

FIG. 2 is a rear view thereof;

FIG. 3 is a first side view thereof; and,

FIG. 4 is a second side view thereof.

The broken lines are included for the purpose of illustrating unclaimed portions of the enclosure for a patient monitor and form no part of the claimed design.

Enclosure for a portable patient monitor with graphic display of physiological patient and treatment data, as well as connectors to external sensors and control elements, for use in a medical office and/or hospital environment.
